C. U. R. A. Patents Limited, London, England

Application February 21, 1948, Serial No. 10,056

6 Claims. (Cl. 110—75)

1

This invention relates to means for controlling the supply of air for combustion of solid carbonaceous fuel in furnaces and like heating appliances of the kind described in U. S. appln. Ser. No. 507,850 (now U. S. Patent No. 2,515,545).

In that specification is described a furnace or like heating appliance in which the rate of heat release and the composition of the combustion gases are independently and simultaneously controllable at will. One form of the heating appliance comprises a hearth, means for feeding solid fuel thereto to maintain thereon a stable combustion bed of fuel having a free surface, means forming a passage for conducting to a zone of use the combustion gases passing from the said free surface, air-jetting apparatus constituting the sole means for supplying combustion air to the said bed and comprising an inlet opening arranged to project the whole of the air for combustion against the said free surface so as to penetrate into the bed therethrough and also comprising means, for example, a fan or blower, for regulating the quantity of air supplied in unit time to establish a definite rate of combustion in the bed, and a regulating device for varying the effective cross sectional area of the said inlet opening for maintaining the pressure therein, and correspondingly the velocity of impingement of the jetted air on to the free surface, at a predetermined value independently of the quantity supplied in unit time.

In operating the appliance the rate of heat release is controlled by controlling the rate of air supply, that is to say the quantity of air supplied in unit time, and the composition of the combustion gases at or near the fuel surface is controlled by controlling the velocity of impingement of the jetted air on to the free surface, whereby the mean penetration of the jetted air into the fuel bed and consequently the composition of the combustion gases is controlled. Thus, it is possible so as to adjust the mean penetration of the jetted air that the combustion gases contain oxygen and combustible products, more especially carbon monoxide, in proportions relatively to one another requisite for their substantially complete conversion into fully burnt products outside the fuel surface, whereby a maximum liberation of heat for a given rate of air supply, and consequently very high temperatures, are attained. Alternatively, the mean penetration can be increased beyond this point to give combustion gases containing a higher proportion of combustible products relatively to oxygen, or it can be decreased to give combustion gases containing

2

a lower proportion of combustible products, and therefore an excess of oxygen.

The regulating device for varying the effective cross sectional area of the inlet opening may be, for example, an adjustable valve for partially obstructing the said opening. Any variation in the rate of air supply, in the absence of any other adjustment, will lead to a change in the pressure of the air in the air-jetting apparatus between the fan or blower and the inlet opening or nozzle. Consequently, when it is desired to alter the rate of heat release by varying the rate of air supply, without alteration of the mean penetration of the air jet into the fuel, an increase in the rate of air supply will necessitate an increase in the effective cross sectional area of the inlet opening in order to maintain the velocity of the air jet substantially constant; and conversely, a decrease in the rate of air supply will necessitate a decrease in the said cross sectional area. Accordingly, two separate adjustments have to be made.

However, the velocity of the air jet emerging from the inlet opening into the furnace is in a general sense a function of the pressure of the air in the air inlet opening. Thus, if the said pressure is maintained constant, the velocity of the jet will also remain substantially constant.

It is an object of the present invention to provide in a heating appliance of the kind described in the aforesaid application Serial No. 507,850 (now U. S. Patent No. 2,514,545), means for automatically maintaining the pressure of air in the said air inlet opening constant or approximately constant when variations are made in the rate of air supply. To this end the two adjustments referred to above are coupled together, and this increases the efficiency of the heating appliance and makes it more suitable for purposes in which it is important to control the composition of the combustion gases.

According to this invention, in a heating appliance of the kind described above there is provided detecting means responsive to variations of pressure in the said inlet opening due to variations in the quantity of air supplied in unit time, and means controlled by the said detecting means for operating the said regulating device to restore the pressure to substantially the predetermined value.

The detecting means responsive to variations of pressure in the air inlet means may take the form of a member capable of displacement by pressure variations in the air inlet means on either side of a mid-position which the member

occupies when the pressure is at or approximately at the value which it is desired to maintain. The displaceable member may be, for example, a piston, a diaphragm, an inverted bell floating in a liquid, or the liquid in a manometer tube. In order that the apparatus may be adjustable to vary the pressure which it is desired to maintain the displaceable member may be provided with regulating means whereby it can be caused to occupy its mid-position at different pressures. Such regulating means may, for example, take the form of adjustable weight or spring loading means acting on the displaceable member. The regulating means may be marked or calibrated in terms of the pressure which it is desired to maintain, or, since the pressure is in a general sense a function of the velocity of the air issuing from the inlet opening, in terms of this velocity. Since the velocity, when other factors are the same, determines the composition of the combustion gases, the said marking or calibration may be in terms of the composition of the combustion gases, provided that other combustion conditions, such as the nature of the fuel and the form and porosity of the fuel bed, are not likely to be changed to any considerable extent.

The displaceable member may be mechanically connected to the device for regulating the inlet opening so as to operate the said device directly, provided that the movements of the displaceable member under action of pressure changes are sufficiently powerful for the purpose. Alternatively, the displaceable member may control the operation of the said regulating device by controlling a supply of energy to actuate independent means for operating the regulating device. Thus, for example, the displaceable member may control the admission of fluid under pressure to a cylinder to move a piston therein connected directly to the regulating device, or it may control the supply of electric current to electrically operated means for actuating the regulating device. In the latter case the displaceable member may, for example, operate a direct current reversing switch to change the direction of rotation of a direct current electric motor adapted to move the regulating device in one direction or the other for increasing or decreasing the effective area of the inlet opening, the switch being inoperative and passing no current when the displaceable member is in its mid-position and being operated when the said member moves to one side or the other of its mid-position.

The pressure to which the detecting means is responsive may be the pressure in the air inlet means with reference to the atmospheric pressure. When, however, material changes of pressure are likely to occur in the combustion space in the vicinity of the air inlet the detecting means may be responsive to the pressure in the air inlet means with reference to the pressure in the said space. Thus, for example, the displaceable member may be subject on one side to the pressure in the air inlet means and on the other to the atmospheric pressure or to the pressure in the combustion space in the vicinity of the air inlet.

As described in application Ser. No. 507,850 (now U. S. Patent No. 2,514,545) the furnace or like heating appliance may comprise two or more air inlets each directing a jet of air on to a different part of the same fuel surface or on to separate fuel surfaces disposed at different parts of the appliance. When a plurality of air inlets is present each inlet may have a device for regulating the effective area of its opening and also

with pressure responsive detecting means to control the operation of the regulating device or a single such detecting means may be used to control all the inlets or groups thereof.

In the case of a plurality of air inlets they may all be connected to a common air supply and capable of being separately closed and opened so as to vary the aggregate area of the inlet openings, for example, as described in British specification No. 12,376 of 1944 (now British Patent No. 587,821). In this arrangement each inlet opening can be regarded as a part of a single inlet opening constituted by the sum of the areas of all the openings, and the number of inlets in operation can be increased or decreased to restore the desired pressure when the rate of supply of the air in the common air supply is increased or decreased. In this case the regulating device may consist of valves provided in the several inlets for completely closing or completely opening the same each independently of the others or in groups of two or more inlets independently of other groups. With this arrangement a single detecting means may be provided responsive to variations of pressure in the common air supply, and the said detecting means may control the closing and opening of the valves of the air inlets or of groups of air inlets in succession until the desired pressure has been restored. For this purpose there may be used as a displaceable member an electrically conductive liquid, such as mercury, in a manometer tube, the liquid in one limb of the tube being subject to the pressure in the common air supply and in the other limb to atmospheric pressure or to the pressure in the combustion space in the vicinity of the air inlets. Each limb of the manometer tube is provided with an electric contact in order to control electrical means, for example, solenoids, for successively opening or closing the valves so long as the liquid in the manometer tube makes contact with one or other of the contacts therein.

Various constructions of automatic control means in accordance with the invention are illustrated in the accompanying drawings, in which:

Figure 1 is a longitudinal section of one construction of a nozzle provided with pressure responsive detecting means.

Figure 2 is a similar section of another construction.

Figure 3 is a similar section of a further construction, and

Figure 4 shows in diagrammatic form a further construction of pressure responsive detecting means and means for controlling a plurality of nozzles.

Figure 5 shows in sectional elevation a furnace provided with automatic control means of the kind shown in Figure 3.

In the several figures like reference numbers are used to denote like parts.

In Figures 1, 2 and 3, a nozzle 10 having an opening 11 is supplied with air through a pipe 12 by means of a fan or blower (not shown). The effective area of the nozzle opening 11 is controlled by means of a valve 13 which is movable to vary the said area.

In Figure 1 the hollow valve 13 is fixed to one end of a tube 14 to which is fixed near the other end thereof a piston 15 movable within a chamber 16. The tube 14 is maintained in an axial position within the nozzle 10 by means of four pins 17 (of which only two are shown) projecting radially inwards from the inside of the nozzle 10. The tube 14 is made hollow in order that the

progress of combustion can be observed from the exterior of the furnace.

The righthand side of the piston 15 is acted on by the air pressure within the nozzle 10 and pipe 12 communicated to the piston through an opening 18 in the chamber 16, and on the other side the piston is acted on by a spring 19 compressed between the piston and a housing 20 formed in the cover 21 of the chamber 16. On the same side the piston 15 is also exposed to atmospheric pressure by means of the opening 22 in the cover 21. The sizes of the openings 18 and 22 are sufficient to enable the piston 15 to respond rapidly to changes in the air pressure acting upon it, but are also small enough to reduce by damping the tendency for the piston to oscillate or "hunt" when it moves in response to a change in pressure. A regulating screw 23 enables the degree of compression of the spring 19 to be regulated.

The movement of the piston 15 is communicated directly to the valve 13 by the connecting tube 14, and the position of the piston and the valve depends on the air pressure in the nozzle 10 and pipe 12 and the counterbalancing pressure of the spring 19 and of the atmosphere. Thus, for any given setting of the regulating screw 23, an initial increase or decrease or pressure in the nozzle caused by altering the air supply rate will move the piston to the left or right, respectively, and so cause an alteration in the effective cross sectional area of the opening 11 sufficient to restore the pressure to approximately its original value for the altered rate of air supply. By changing the setting of the regulating screw 23 the pressure which it is desired to maintain in the nozzle can be altered. It will be understood that, owing to the increase in the force required to balance the pressure of the spring 19 as it becomes more compressed, the air pressure cannot be restored to exactly its original value. However, by using a spring of suitable characteristics it is possible to arrange that an approximately constant pressure adequate for practical purposes is maintained.

In the construction shown in Figure 2, the nozzle 10 has an opening 11 in the form of a rectangular slot, and the valve 13 takes the form of a tongue movable across the opening 11 to vary its effective area. The tongue 13 is provided with a plate 24 to which is attached a rod 14, the plate 24 also serving to maintain the tongue 13 in position within the nozzle 10. At the other end of the rod 14 is fixed a piston 25 movable within a cylinder 26. The piston is moved by a fluid under pressure, such as oil, introduced into the cylinder on one or other side of the piston as hereinafter described. The air pressure in the nozzle 10 and inlet 12 is communicated through a duct 27 to the lower side of a diaphragm 28 mounted in a chamber 29. A spring 30 acts on the upper side of the diaphragm 28, and the latter is also subjected on that side by means of a narrow tube 31 to the pressure prevailing in the furnace in the vicinity of the nozzle opening 11. The pressure exerted on the diaphragm 28 by the spring 30 is so adjusted by means of a regulating screw 32, which can be locked by a nut 33, that the diaphragm assumes substantially its mid-position under the counterbalancing pressure which it is desired to maintain in the nozzle 10.

To the centre of the diaphragm 28 is fixed a cylindrical slide valve 34 movable within a bore 35. The slide valve 34 comprises a central portion of reduced diameter between two blocking

members 36 and 37, of full diameter, and two further portions of reduced diameter on the other sides of the members 36 and 37. The member 36 controls a duct 38 for admitting fluid under pressure into the cylinder 26 on the lefthand side of the piston 25, and the member 37 controls a duct 39 for admitting such fluid into the cylinder 26 on the other side of the piston. The fluid is introduced through a duct 40 into the space between the members 36 and 37, but is unable to enter the cylinder 26, when the diaphragm 28 and valve 34 are in the mid-position, since the ducts 38 and 39 are then closed by the members 36 and 37, respectively. When the pressure in the nozzle 10 increases or decreases due to a change in the rate of air supply, the diaphragm 28 and with it the valve 34 moves up or down, respectively. An upward movement of the valve 34 causes the member 37 to open the duct 39 and the member 36 to open the duct 38, thereby enabling fluid to pass from the duct 40 through the duct 39 into the cylinder 26 on the righthand side of the piston 25, and also enabling fluid to pass from the other side of the piston through the duct 38 and into a duct 41 communicating with a duct 42 for the discharge of the fluid. Accordingly, the piston 25 moves to the left and carries with it the tongue 13 to increase the effective area of the opening 11. As the pressure falls in the nozzle 10 the diaphragm 28 and valve 34 will descend, and when the pressure is restored to the original value the diaphragm and valve will have reached the mid-position in which the flow of fluid to and from the cylinder 26 is shut off by the blocking members 36 and 37. The piston 25 and tongue 13 are thus locked in their new position. A downward movement of the diaphragm 28 and valve 34, due to a decrease in pressure consequent upon a reduction in the rate of air supply, again causes the members 36 and 37 to open the ducts 38 and 39, but in this case the duct 36 is put into communication with the supply duct 40 and the duct 39 into communication with a duct 43 which in turn communicates with the discharge duct 42. Thus, fluid is introduced into the cylinder 26 on the lefthand side of the piston 25 and discharged from the cylinder on the other side of the piston, which therefore moves to the right to reduce the effective area of the opening 11. When the pressure in the nozzle increases to the original value the diaphragm 28 and valve 34 will return to the mid-position, and the piston 25 and tongue 13 will be locked in their new position.

The supply of fluid under pressure used to operate the piston 25 may advantageously be derived from some source associated with the furnace or other heating appliance. For example, if the furnace is part of a steam generator, the duct 40 may be connected to the boiler feed pump. Alternatively, if the furnace is part of a transportable steam boiler unit of the kind described in British specification No. 12,376 of 1944 (now British Patent No. 587,821) fitted to a vehicle, the duct 40 could be connected to a high pressure oil lubricating system on the vehicle.

In the construction shown in Figure 3, the nozzle 10, opening 11 and tongue 13 are similar to those shown in Figure 2. The rod 14 is similarly connected at one end to the plate 24 of the tongue 13, but its other end is screw-threaded as shown at 50. On the screw-threaded portion 50 is screwed a pinion 51 which engages a worm gear 52 driven by a direct current electric motor

53. The pinion 51 is secured against axial movement along the portion 50 of the rod 14 between a bearing 54 and a bush 55, in which bearing and bush the portion 50 of the rod is free to move longitudinally.

The pressure responsive detecting means consists of an inverted bell 56 floating in an oil bath 57. The interior of the bell 56 is in communication with the pressure in the pipe 12 by means of a conduit 58. The weight of the bell required to counterbalance the pressure which it is desired to maintain in the inlet 12 is adjustable by means of detachable weights 59. At the top of the bell 56 is connected a switch arm 60 which turns upon a fixed pivot 61 and carries a pair of contact plates 62 and 63 adapted to make and break contact with a pair of fixed contact plates 64 and 65. The other end of the arm 60 carries a contact 66 adapted to engage one or other of two contacts 67 and 68. The contacts 62, 63, 64 and 65 constitute a switch for reversing the direction of the current supplied from a battery 69 to the field winding of the electric motor 53. The leads 70 supply current to the field winding, and the leads 71 supply current to the armature winding. The leads 70 are connected to the contacts 64 and 65 so that the direction of the current energising the field winding can be reversed, while the leads 71 are permanently connected to earth and the contact 63 so that the current energising the armature winding always flows in the same direction. When the bell is in its uppermost position contact 66 engages contact 67, contact 63 engages contact 64, and contact 62 engages contact 65. In this position, therefore, the contact 64 is connected to the positive pole of the battery 69, and the contact 65 is connected to the negative pole through the earth and the leads 72 connected to the contact 62. Conversely, in the lowermost position of the bell the contact 66 engages contact 68, contact 63 engages contact 65, and contact 62 engages contact 64, so that contact 64 is then connected to the negative pole and contact 65 to the positive pole, thus reversing the direction of the current in the field winding.

The skirt of the bell 56 is sufficiently light to ensure that when a slight change of pressure occurs in the pipe 12 the bell will continue to rise or fall until the contacts 66, 67 or 68, 65 are closed, and that the bell will return to its original position when the pressure has been restored to substantially its original value. In the balanced or mid-position of the bell no current is supplied to the motor 53. When an increase in pressure in the pipe 12 occurs due to an increase in the rate of air supply, the bell ascends to its uppermost position so that the motor is energized to drive it in the direction required to retract the tongue 13 and so increase the area of the nozzle opening 11. A reduction in pressure in the pipe 12, on the other hand, causes the bell to descend so that the motor is driven in the reverse direction to advance the tongue 13 and so reduce the area of the nozzle opening 11. In both cases, when the pressure has been restored to substantially its original value by the adjustment of the opening 11, the bell 56 will return to its mid-position in which the contact 66 is not touching either of the contacts 67 and 68. By changing the weights 59 on the bell the pressure which it is desired to maintain in the nozzle can be altered. The sensitivity of the device depends on the lightness in weight of that portion of the skirt of the bell which moves into

and out of the oil during changes in the air pressure.

In the construction shown in Figure 4, there is a plurality of rods 14, of which only two marked 5 14 and 14a are shown, and each of which controls one of a plurality of nozzles (not shown) connected to a common air supply main. Each rod 14 operates a valve (not shown) whereby the air supply to the respective nozzle can be 10 either fully admitted or completely shut off. Thus, the aggregate area of the nozzles in operation can be varied to maintain an approximately constant pressure in the operative nozzles when changes are made in the rate of air supply. The arrangement of nozzles and valves may be similar to that shown in Figures 2 and 3 of British specification No. 12,376 of 1944 (now British Patent No. 587,821).

The pressure responsive detecting means consists of a U-tube 80 containing an electrically conductive liquid, for example, mercury. One end 81 of the tube communicates with the common air supply main between the fan or blower and the nozzles, and the other end 82 is in communication with the combustion space in the furnace in the vicinity of the nozzles. In the limbs 83 and 84 of the tube 80 are provided contacts 85 and 86, respectively. The vertical distance between these contacts can be varied by adjusting the tilt of the tube 80 by means of a set screw 87 against which rests an abutment 88 at the bottom of the tube 80. This vertical distance is so adjusted that when the pressure in the supply main is at the value which it is desired to maintain, the liquid in the tube occupies a mid-position in which it does not make contact with either of the contacts 85 and 86.

When an increase in the rate of air supply causes an increase in pressure in the supply main, 40 the liquid in the limb 83 rises until it reaches the contact 85, thus closing the circuit of a solenoid 89 from a battery 90 through leads 91 and 92, the lower contacts of a switch 93 and to the battery through the earth. When thus energised, the solenoid 89 attracts an armature 94 connected to the rod 14, which is thus pulled to the left to open the valve of the nozzle controlled thereby. At the end of its travel the armature 94 operates the switch 93 by means of a lug 95 so as to open the lower pair of contacts and close the upper pair of contacts. In this manner the circuit of the solenoid 89 is broken, and the current diverted through a lead 96 and the lower contacts (when closed) of a switch 93a 55 to energise a solenoid 89a, which attracts an armature 94a connected to a second rod 14a which opens the valve of a further nozzle. If, however, during the opening of the first valve controlled by the rod 14 such a reduction in pressure in the air supply main occurs that the liquid in the tube 80 returns to its mid-position and breaks the battery circuit, the solenoid 89a will not be energised and the valve controlled by the rod 14a will not be opened. It will be understood that there are further solenoid units (not shown) each comprising a solenoid 89, switch 93, armature 94 and rod 14, and that if, after the opening of the second valve controlled by the rod 14a, the battery circuit is not broken by 60 the liquid in the tube 80, the succeeding units will be operated in turn until the liquid returns to its mid-position.

When a reduction in the rate of air supply causes the pressure in the supply main to fall, 65 the liquid in the limb 84 rises until it reaches the

contact 86, thus closing the circuit of a solenoid 97 from the battery 90 through leads 91 and 98, the lower contacts (when closed) of a switch 99, and to the battery through the earth. When thus energised, the solenoid 97 attracts the armature 94 and so pulls the rod 14 to the right to close the valve of the nozzle controlled thereby. At the end of its travel the armature 94 operates by means of a lug 100 the switch 99 to cut out the solenoid 97 and energise a solenoid 97a in the 10 manner described in connection with the solenoid 89a.

The solenoid units may, if desired, be so interconnected that the order in which the nozzle valves are opened is not the exact reverse of the order in which they are closed. In this way a more even distribution of the combustion air over the fuel bed can be secured. If desired, each rod 14 may control more than one valve, and the rods may operate the valves electrically.

It will be understood that the pressure responsive detecting means and valve actuating means of the various constructions shown in the drawings can be modified, and are in many cases interchangeable. For example, a single rod 14 as shown in Figures 1, 2 or 3 could simultaneously operate a plurality of valves or tongues 13 each in a separate nozzle, or could operate in succession a series of nozzle valves of the kind operated by the rods 14, 14a etc. in Figure 4. An alternative means to that shown in Figure 4 for operating the radially arranged nozzle valves in the transportable steam generator shown in Figures 2 and 3 of British specification No. 12,376 of 1944 (now British Patent No. 587,821), comprises an actuating ring adapted on rotation in one direction or the other to open or close, respectively, the nozzle valves in succession, as is the sequential valve opener of U. S. Patent No. 1,630,977, issued May 31, 1927, to Smoot. For example, for every given number of degrees of rotation, say 2°, in one direction or the other the actuating ring would open or close a single valve or a group of two or more valves. The ring could be operated by a single rod actuated by pressure responsive detecting means in the same manner as the rod 14 in Figures 1, 2 or 3.

In Fig. 5 is shown a furnace constructed in accordance with this invention. The furnace, which is constructed and operates in the manner described in United States Patent No. 2,515,545, comprises a refractory rear wall 110, hearth 111, front wall 112 and roof 113 enclosing a combustion space 114 and fuel bed 115. Solid carbonaceous fuel is fed under gravity from a fuel hopper 116 to the fuel bed. The hopper 116 has a fuel charging opening 117 at the top which is closed air-tight by means of a cover 118. The combustion gases issuing from the free surface 119 of the fuel bed 115 pass through a passage 120 to a zone (not shown) in which the sensible and potential heat of the combustion gases is utilized for some heating purposes, for example, for generating steam. The air for combustion of the fuel is directed in the form of a jet against the free surface of the fuel bed by means of a nozzle 10 of the kind shown in Figure 3, which is provided with a tongue 13 controlling the size of the opening, the tongue being moved by the rod 114 which is actuated by an electric motor 53 through the transmission means 50, 51, 52 and 55 as described above. The motor is operated through the leads 70 and 71 by the pressure responsive means and electric contact means shown in Figure 3, the bell 56 shown in that figure being

in communication with the pipe 12 through the conduit 58. Combustion air is supplied under pressure to the nozzle 10 through the pipe 12 by means of an electrically driven variable speed blower 121. The quantity of air supplied to the fuel bed in unit time is controlled by regulating the speed of the blower 121 as by means of a rheostat 122 connected in the leads 123 supplying current for driving the blower. When the speed of the blower is changed to increase or decrease the quantity of air so supplied, the pressure in the nozzle 10, and consequently the velocity of the air issuing from the opening 11, increases or decreases. The tongue 13 is moved automatically to increase or decrease the size of the opening 11 by the control means shown in Figure 3, so as to restore the said pressure and velocity to substantially the value predetermined for maintaining a given extent of penetration of the air into the fuel bed and correspondingly a given composition of combustion gases issuing from the fuel bed, notwithstanding the change in the quantity of combustion air supplied to the fuel bed.

While there have been described herein what are at present considered preferred embodiments of the invention, it will be obvious to those skilled in the art that minor modifications and changes may be made therein without departing from the essence of the invention. It is therefore to be understood that the exemplary embodiments are illustrative and not restrictive of the invention, the scope of which is defined in the appended claims, and that all modifications that come within the meaning and range of equivalency of the claims are intended to be included therein.

Having now particularly described and ascertained the nature of our said invention and in what manner the same is to be performed, we declare that what we claim is:

40. 1. A heating appliance for the combustion of solid carbonaceous fuel comprising a hearth, means for feeding solid fuel thereto to maintain thereon a stable combustion bed of fuel having a free surface, means forming a passage for conducting to a zone of use the combustion gases passing from the said free surface, air-jetting apparatus constituting the sole means for supplying combustion air to the said bed and comprising nozzle means arranged to project the said air against the said free surface so as to penetrate into the bed therethrough and also comprising means for regulating the quantity of air supplied in unit time to establish a definite rate of combustion in the bed, a regulating device for varying the effective cross sectional area of the said nozzle means for maintaining the pressure therein at a predetermined value independently of the quantity supplied in unit time, detecting means responsive to variations of pressure in the said nozzle means due to variations in the quantity of air supplied in unit time, and means controlled by the said detecting means and operatively connected to the said regulating device for operating the latter to restore the pressure to substantially the predetermined value.
45. 2. A heating appliance as claimed in claim 1, wherein the pressure responsive detecting means is a displaceable member subjected to the pressure in the nozzle means and displaced by variations in the said pressure on either side of a midpoint position which the member occupies when the pressure is substantially at the predetermined value.
50. 3. A heating appliance as claimed in claim 2, wherein the means controlled by the displaceable

member for operating the regulating device is a mechanical connection between the said member and device for operating the latter directly.

4. A heating appliance as claimed in claim 2, wherein the means controlled by the displaceable member for operating the regulating device comprises a source of fluid pressure and a cylinder containing a piston operatively connected to the regulating device and actuated by the admission to the cylinder of fluid, the admission of which is controlled by the displaceable member.

5. A heating appliance as claimed in claim 2, wherein the means controlled by the displaceable member comprises electrically actuated means operatively connected to the regulating device and switch means operated by the displaceable member and connected in the circuit supplying electric current to the said electrically actuated means.

6. A heating appliance as claimed in claim 5, wherein the electrically actuated means is a direct current electric motor in driving connection with the regulating device for moving the latter to increase the effective cross sectional area of the nozzle means in one direction of rotation of the motor and to decrease the said area in the opposite direction of rotation, and the displaceable

member is operatively connected to a direct current reversing switch connected in the circuit supplying current to the said motor and operated by the displaceable member to reverse the current when the said member moves from one side to the other side of its mid-position.

MEREDITH WOOLDRIDGE THRING.
FRITZ BRUNO KARTHAUSER.
